[57] ABSTRACT

An action football board game comprising an elongated plastic insert base having a multifaceted ball or die receiving area at one end, a defense strategy compartment at the other end with special mechanism for predetermining the position of an offensive play card according to the defense strategy employed, and a central area over which a simulated football field is superimposed on a container for the insert having the usual ball and yardage markers and score and time indications. The predetermining mechanism include card abutment pegs inserted through holes in the insert which are labelled for the particular defensive maneuver the player on defense wishes to employ.

SHEET 3 OF 3

FOOTBALL GAME

The invention relates to action board games of the parlor type and, in particular, to such games relating to the American game of football.

The present football game has two basic components, namely a plastic insert base which provides score board components and a specially configurated area in which an offensive play card is selectively positioned according to the strategy that the defensive player wishes to employ, and a container for the insert bearing a simulated field of play. The container provides a results window through which yardage gained or lost is read off the play card and additional windows through which scoring and time indications are shown. Preferably the insert provides a depressed portion designated as the result bowl into which a specially shaped die is tossed to indicate according to color the particular column of numbers on the play card to be used in determining yardage lost or gained on successive plays of the game.

One object of the game is to provide an indoor football board game of economic construction and providing a unique mode of defensive and offensive game play.

Other objects and advantages of the invention may be appreciated on reading the following description of one embodiment taken in conjunction with the accompanying drawings, in which:

FIG. 1 is a top plan view of the game board as it might appear during play;

FIG. 2 is a view in cross section showing the result bowl in the game board for receiving the toss of the result ball and taken on the line 2-2 of FIG. 1;

FIG. 3 is a view in cross section showing the game board insert taken on the line 3-3 of FIG. 1;

FIG. 4 is a view in cross section through the defense strategy region and showing the offensive play card in position in the action slot for determining the yardage gained or lost taken on the line 4-4 of FIG. 1;

FIG. 5 is a partial sectional view of the defense strategy region and action slot taken on the line 5-5 of FIG. 1; and

FIG. 6 is a plan view partially in section of the defense strategy region and action slot for yardage determination of the insert taken on the line 6-6 of FIG. 5.

Referring to the drawings, the board game comprises an insert 10 and its container 12. The insert 10 provides a result bowl 14 formed as a depression at one end of the top surface 16 of the insert, FIG. 2. Along the top edge of the insert are bosses 18 on which are mounted rotatable wheel cards 20 and 21 bearing home and visitor's team scoring indicia and down, quarter and time to play data, respectively.

As best seen in FIGS. 1, 4, 5 and 6 a transverse action slot 22 is formed in the surface 16 at the other end of the game board. Disposed and overlying the upper half portion of the action slot is defense card 24 having a column of "run" holes 26 on one side and "pass" holes 28 on the other side which extend through both the card and the insert, the holes being appropriately labelled on the card with identifying defensive plays and formations. Pegs 30 are selectively inserted in the holes 26 and the holes 28 according to the type of defense the defending player anticipates should be established for either a running play or a pass play to be determined by the offensive player as will be seen.

The container 12, FIG. 1, for the insert 10 is provided with a simulated football field area 32 in its central por-

tion. There is provided in the center of the area 32 longitudinal slot 34 for slidable football marker 36 and along the top edge of the field area 32 is a second slot 38 into which yardage marker 40 is slidably inserted.

Formed in the insert 10, FIG. 3, are elongated depending ribs 42 and 44 which are disposed directly underneath the slots 34 and 38, respectively, serving the dual purpose of imparting a degree of rigidity to the plastic insert 10 and providing clearance for the ball and yardage markers as their positions are moved as the play progresses. As scores are made by the teams, they are registered on the card wheels 20 and down, quarter and time information is recorded on the card wheels 21, the wheels 20 and 21 being seen through windows 40 and 42, respectively, in the container 12.

The container 12 is provided at one end with a large opening 46 disposed in registry with the result bowl 14 formed in the insert.

At the other end of the container is a mask 48 hinged to the surface of the container and having a defensive and offensive play indicating window 50 located in the defense strategy region 52 of the board, the mask being adapted to overlie the defense card 24. Below the mask 48 is result window 54 formed longitudinally in the surface of the container through which yard gained or lost is read out.

In the play of the game the offensive player inserts into the action slot 22 an offensive play card 56. One side of the card has readout yardage information for pass plays and the other side for running plays. The information is arranged in columns 58 which are separately colored, the columns being selectively employed for readout according to the color which is turned up in the result bowl 14 on the toss of multifaceted and colored die 60 in the result bowl. The card 56 has formed therein lateral shoulders 62 and 64, the higher shoulder being used to determine the depth of penetration of the card into the action slot as it moves against a peg 30 which has been previously placed by the defensive player in one of the holes in each of the columns of holes 26 and 28 according to his chosen defense formation or play for both running and passing plays. The yardage gained or lost is then determined by looking through the readout or results window 54 which reveal one row of figures selected from the variously colored columns. Besides pass and run play cards, cards are also provided for kick-off and kick-off return plays.

What is claimed is:

1. In a football board game, a board surface adapted to have superposed thereon a simulated football field, a container for said board surface bearing a simulated football field and having a slidable ball marker thereon, said board surface providing a defensive strategy region having an action slot formed therein, said action slot having formed therein a plurality of holes arranged in a column along each longitudinal edge of said slot and having defensive play indicia disposed proximate to each of said holes, pegs adapted to be selectively inserted in said holes, offensive play cards adapted to be inserted in said slot having play result indicia disposed on both surfaces thereof with the indicia on one surface being different from the indicia on the other surface and having a shoulder formed along each lateral edge thereof, one lateral shoulder being at a different longitudinal location from that of the other lateral shoulder on each play card, whereby one of said play cards may

be inserted in said slot and its longitudinal penetration in said slot being determined by means of said pegs engaging one of said shoulders depending upon which side of the card is face up.

2. In a game as defined in claim 1 a windowed mask hingedly connected to said board surface adapted to reveal said defensive play indicia when in closed position.

3. In a game as defined in claim 2 wherein said play result indicia comprises yardage gained or lost indicia

arranged in columns on said play cards, said columns being differently colored.

4. In a game as defined in claim 3 a multifaceted die, each facet being colored to determine the column of figures indicating yardage gained or lost on the play card for controlling the movement of said ball marker according to the color of the upturned facet of the thrown die matching the coloration of the column thereby selected.
